SUPPORT FOR A LIGHTING FIXTURE

Jack D. Steinhorn, Bronx, N.Y., assignor to Swivelier Company, Inc., Nanuet, N.Y., a corporation of New York

Filed Sept. 3, 1964, Ser. No. 81,592

Term of patent 14 years

(Cl. D48—4)

The dotted line showings in FIGURES 1—5 inclusive are for illustrative purposes only.

I claim:

The ornamental design for a support for a lighting fixture, as shown and described.
